LIME SLAKING APPARATUS

Elmer E. Harper, Kansas City, Mo.

Application May 13, 1929. Serial No. 362,606

4 Claims. (Cl. 23—287)

The present invention relates to lime slaking apparatus, and aims to provide an improved and unique construction which is entirely automatic in its operation and possesses various novel 5 characteristics directed to a marked improvement in the efficiency of such apparatus.

Accordingly, the invention comprises a slaking receptacle having means for maintaining a continuous automatic feed of the material to be 10 slaked into the receptacle, and also means for furnishing a properly regulated supply of water as required for the slaking operation.

The receptacle construction comprises both slaking and dilution compartments, with provision 15 for varying the relative sizes of the two compartments, as by varying the position of the overflow partition between them. A further feature of the invention resides in the provision of automatic means constantly removing the vapor and dust-laden air from above the surface 20 of the contents within the slaking and dilution compartments, thereby keeping the air around the machine pure as well as promoting the efficiency of the operation of the material-feeding 25 mechanism.

Further features of my invention comprise improvements of the receptacle structure, including the discharge outlet for the unslaked material from the slaking compartment, the 30 inlet ports for the water supply to both the slaking and dilution compartments, and the selective regulation or control of said water supply as required for slaking and dilution purposes.

A still further object of the invention is the 35 provision of improved mechanical mixing devices for agitating the contents of the apparatus, the same being adapted for effective engagement with the material while automatically yielding to any necessary extent as required by the deflecting action of the material.

With the foregoing general objects in view, as well as various minor objects as will appear in the course of the detailed specification, the 45 invention will now be described by reference to the accompanying drawings illustrating one practical form of embodiment of my improvements, after which the various features and combinations deemed to be novel will be set forth and claimed.

50 In the drawings—

Figure 1 is a front elevation illustrating an apparatus constructed in accordance with the present invention;

55 Figure 2 is a plan view with the material-feeding machine omitted;

Figure 3 is a longitudinal vertical sectional view of the apparatus;

Figure 4 is a vertical transverse section, taken on the line IV—IV of Figure 1;

Figure 5 is an enlarged longitudinal sectional detail of the shaft terminals, illustrating the 60 water connections and inlet ports around the shaft;

Figure 6 is an enlarged transverse sectional detail, showing one of the material-engaging 65 and agitating elements.

Referring now to said drawings in detail, the apparatus is illustrated therein as comprising a receptacle construction 10 of any appropriate material such as sheet metal, which may be 70 made up in trough form as shown, having the curved bottom 12, and supporting legs 14, and a cover member 16 extending over the top of the entire receptacle.

The interior of the receptacle may be divided 75 by a vertical overflow partition 17 into a main slaking compartment 20 and a smaller dilution compartment 18. Preferably, provision is made for adjusting the position of the partition 17, as by providing a plurality of longitudinally spaced 80 channels or recesses 22 for seating the edges of the partition (see Figures 3 and 4), thereby enabling the relative sizes of the slaking and dilution compartments to be changed to a certain extent, according to the requirements. The 85 final product of lime solution leaves the dilution compartment by way of an overflow opening 23 at the corresponding end of the receptacle (Figures 2 and 3); at the opposite end of the receptacle, the cover member is provided with an opening 24, over which is mounted an automatic material-feeding machine, designated generally by the reference numeral 25, this machine being in all essential respects of the type described in my co-pending patent application, 90 Serial Number 268,516 and designed to discharge the lime material through the opening 24 into the compartment 20 at a given rate according to the rate of speed for which said machine is set, as required by the capacity of the slaking 95 apparatus itself.

Over another opening 30, in the cover member 16, in communication with the upper air space in the dilution compartment 18, is provided a conduit passageway leading to an exhaust or suction device, such as a special type of exhaust fan 32, adapted to be driven by a belt 33 from a suitable motor 34 (Figures 1 and 2).

This arrangement serves to remove any vapors 110 or dust-laden air in the space over the con-

tents of the receptacle and directly beneath the cover member, and the exhaust port 35 of the fan will of course be connected with any suitable conduit (not shown) for conducting the 5 dust and waste vapors to any desired point remote from the apparatus.

The motor 34 is also connected by a belt 38 to the pulley 39 of a reduction gearing 40 which is operatively connected by a driven sprocket 41 10 and sprocket chain 42 to a driven sprocket wheel 43 mounted on one end of a shaft 44 which extends longitudinally through the receptacle and through openings 45 in the end walls 46 thereof. The ends of this shaft 44 are journaled in suitable bearings 48 mounted on transverse frame pieces 49 carried at the ends of longitudinal frame members 50 supported by the legs 14.

At spaced intervals along the shaft 44, the 20 same is provided with stirring or mixing members extending in various different radial directions for agitating the contents of both the slaking and dilution chambers, each of said members comprising a spring or resilient arm 52, as of spring steel, of a bowed contour approaching 25 a spiral outline (see Figures 4 and 6). The free straight-end portion of each arm carries a suitable blade or paddle element 54, and the bowed end of each arm is attached to the shaft (which is of square cross-section) by means of 30 bolts 55 and a set of clamping plates 56 adapted to permit adjustment, or the removal of the arms, at any time, as for repair purposes. The curved or bowed contour of the arms is such as to 35 permit a yielding movement of the blades 54 in both circumferential and radial directions, in response to the dragging action of the material in the receptacle, or on meeting large and hard particles of the material which might otherwise injure the paddle construction.

40 The partition member 17 is provided with an opening 60 for the shaft 44, which opening is of sufficient vertical extent to permit raising of the partition in shifting it from one to another of the channels or recesses 22 in the aforesaid 45 adjustment of the partition, the lower portion of the opening 60 being provided with a movable shutter element 62.

50 A drain outlet 64 is provided at the discharge end of the receptacle, and from the discharge end of the slaking compartment a chute or clinker outlet passage 65 is provided on that side of the receptacle corresponding to the direction of the operative movement of the stirring or 55 mixing paddles 54 in traversing the bottom 12 of the receptacle, said movement thereby tending to impel the unslaked material in the direction of the mouth of said chute or clinker outlet 65. The bottom of said chute or outlet passage 65 is 60 inclined downwardly (Figure 4), and the same is provided with an outlet 66 at any suitable point (Figures 2 and 4), from which the discharge may be regulated in any desired manner—not herein illustrated.

65 For maintaining the necessary supply of water to the apparatus, a water feed pipe 68 leads from any source of water supply under pressure, to a T 69 from which two branch pipes 70-71 lead to the slaking and dilution compartments, 70 respectively. Communication is made with the compartments through the aforesaid openings 45 in the end walls of the receptacle by the way of annular orifices or ports 72 formed by collars 73 mounted on the corresponding end portions 75 of the shaft 44 and registering with the openings

45, as illustrated in Figure 5. The ends of the pipes 70-71, are threaded into these collars into communication with the respective orifices 72, and the outer portions of the collars are formed as packing sleeves fitted with glands 75 having flanges 76 held in place by screws 77 (Figures 1 and 3).

The flow of water to each of the receptacle compartments is separately regulated by suitable valves 80, and in addition the branch pipe 70 is provided with a pressure reducing device 82 as well as a pressure cock 83 for maintaining a certain fixed pressure as indicated by the gauge 84. Other instruments may also be provided, such as a meter, as indicated at 85, and a thermometer 86 carried by the cover member 16 in position to register the temperature of the space within the receptacle beneath the cover.

90 A practical and economical apparatus is thus provided for filling the desired objects of the invention, the same being very efficient, accurate and entirely automatic in its operation. The material feeding machine is set for feeding the lime material into the slaking chamber at the required rate according to the capacity of the 100 slaking apparatus, and the valve mechanism is regulated to supply a uniform supply of water to each of the compartments as required for the slaking operation. The drive connections from 105 the motor operate both the mechanical mixing or agitating mechanism and the exhaust fan of the device, thereby producing a thorough stirring and mixing of the contents of the receptacle to insure proper slaking of the lime, the unslaked particles being propelled out through the discharge chute. The operation of the exhaust fan removes the dust and vapors or fumes from the 110 top of the slaking and dilution chambers, and keeps the feed opening 24 clear so as not to interfere with the feed operation, besides maintaining the air around the apparatus free of such 115 dust and vapors.

120 The blades or paddles 54 operate with a yielding action to impel the material in the stirring or mixing action, their capacity for combined radial and circumferential movements serving to compensate for the thrust offered by solid 125 particles of the material and maintain the necessary contact with such particles for impelling them forward, as said blades traverse the interior of the trough-like bottom 12, as indicated by the broken lines in Figure 6. This results in an efficient and thorough agitation of the contents of the receptacle, without any danger of breaking the stirring arms 52. Any such 130 solid particles as remain in an unslaked form are gradually pushed out into the discharge chute 55, so as no longer to obstruct the stirring mechanism. The arrangement of the water supply connections is such that the flow of water into the receptacle can be regulated as required for the separate compartments, and feeding the water supply axially or along the central longitudinal lines of the receptacle gives 135 an even and uniform distribution of the flow; and the method of mounting the shaft 44 with the bearings outside and the water ports between the receptacle walls and the stuffing boxes protects the latter from any injurious contact with gritty material.

140 As the water flow is continuous, the solution from the slaking chamber 20 overflows the partition 17 continuously into the chamber 18 for further dilution by the flow of water into the 150

latter chamber, and from there overflows through the final discharge opening 23. As in some cases, according to conditions, the relative size of the slaking and dilution compartments may need to be varied, this can be readily done by simply shifting the position of the vertical overflow partition 17, as above explained.

While the intake portion 31 of the fan 32 might, if desired, be placed in direct communication with the outlet openings 30 of the dilution compartment 18, I prefer to interpose a washing and condensation structure between the dilution compartment and the fan. For this purpose, I provide a cabinet or housing 90 divided by a number of spaced vertical baffle partitions 91, 92, into interior compartments 93, so arranged that the vapors are drawn through the openings 30 upward into the first compartment 93, and over the first partition 91 into the second compartment 93 (being the middle compartment in the illustrated construction), and thence beneath the second partition 92 into the next succeeding compartment 93, and so on according to the number of partitions employed. From the last compartment 93 the vapors are drawn upward through an opening 94 into the intake portion 31 of the fan. Water-spray pipes 95 are provided in all but the last compartment 93 for emitting upwardly directed sprays or jets of water therein (see Figure 3), which is allowed to drain through openings 96 provided at the base of each partition 91 back to the openings 30. The operation of this feature of the construction effects a condensation of the warm vapors drawn from the dilution compartment and thereby lightens to that extent the duty of the fan; and also washes the vapors of solid dust particles, which are thus not allowed to reach the fan where they would gradually tend to clog the impellers and impede the fan's action. Moreover, the water supplied by the spray pipes 95 may be utilized to furnish a part of the supply required for the dilution compartment 18.

While I have illustrated and described one practical form of construction for embodying the several features of my improvements, it is apparent that the apparatus is susceptible of many

minor changes in detail (such as the inclusion of a thermostatic control feature if found desirable, and the like) while not departing from the primary aspects of the invention; I therefore desire to be understood as reserving the right to make all such changes or modifications as may fairly fall within the scope of the appended claims.

Having thus described my invention, what I claim and desire to secure by Letters Patent is:

1. Lime slaking apparatus comprising a receptacle, an overflow partition separating the interior of the receptacle into a slaking compartment and a dilution compartment, a longitudinal shaft extending through said partition and both ends of the receptacle and carrying stirring members for agitating the contents of both of said compartments, and water supply means provided with connections forming an annular inlet port around said shaft and through the end walls of the receptacle to both of said compartments.

2. Lime slaking apparatus comprising a receptacle, mechanical agitating means comprising a shaft provided with stirring arms, bearings for said shaft, and water supply means comprising a connection providing an annular inlet port around the shaft and through the corresponding end wall of the receptacle and independent of the bearings of the shaft.

3. Lime slaking apparatus comprising a receptacle, mechanical agitating means comprising a shaft provided with bearings outside the receptacle and stirring arms operating inside the receptacle, and water supply means comprising a connection providing an annular inlet port around the shaft and through the corresponding end wall of the receptacle.

4. Lime slaking apparatus comprising a receptacle, mechanical agitating means comprising a shaft extending through one of the walls of the receptacle, and water supply means including a pipe connected with a collar provided with a packing gland embracing the shaft, said collar being formed with an annular inlet port surrounding the shaft between said gland and the corresponding wall of the receptacle.
